BRACELET FORMED OF DETACHABLE LINKS
HAVING RESILIENT PIN-RETAINING MEANS
THEREINNorman C. Burkhardt, Brookville, N.Y., assignor to
Jacoby-Bender, Inc., Woodside, N.Y., a corporation of
New YorkFiled Oct. 20, 1959, Ser. No. 847,589
5 Claims. (Cl. 59—82)

The present invention relates to a structure for articulately connecting the links of a bracelet chain while permitting ready detachment of links from the chain.

A major problem involved in the merchandising of link chain bracelets, whether used as such or in conjunction with wrist watches, derives from the fact that the wrist sizes of prospective customers vary widely. The problem is particularly critical when the bracelet is used to attach a wrist watch, since then the bracelet must fit the wrist rather snugly. Since bracelets are available in many different styles, it has been necessary for the retailer to stock a given bracelet in various sizes in order to be able to fit the wrist of the particular customer who wishes to purchase that bracelet. Since the retail jeweler has only a limited amount of money to invest in bracelet inventory, it follows that, except in the most unusual circumstances, he is as a practical matter unable to stock all bracelets in all sizes. As a result he often loses a sale because he does not have the particular bracelet desired by a prospective purchaser in the proper size.

This problem has long been recognized, and the art is replete with link chain structures so designed that the jeweler, at the point of sale, may add or subtract links from the chain in order to bring it to the proper size for the particular customer involved. These link attaching arrangements have in general suffered from one or more of the following disadvantages: The manipulation involved in attaching and detaching links is complicated, difficult, and time consuming; special tools are required; complex structures are involved which make for expense of manufacture and unreliability of operation; because of the attaching and detaching structure the links are excessively bulky or are visually unattractive; accidental separation of links occurs all too frequently; the articulation of the links relative to one another is inhibited or unduly restricted.

In accordance with the present invention a simple structure has been devised which eliminates all of the above mentioned disadvantages. In non-detachable linkages the links are often connected together by means of pin-like securing elements which define pivotal axes about which adjacent links can turn. Obviously detachability of links can be effected if these link-securing pins are removed. The problem is, however, not nearly as simple as that statement might imply. If the pins are readily removable they will tend to escape from the links accidentally, an inadmissible situation. If the pins are reliably secured in place the problem of removing them when link detachment is desired becomes overly delicate and complicated. Hence, despite the apparent obviousness of this general approach to the problem, this method of detachability has not in the past proved practical, as witness the considerably more complicated detachability arrangements in the prior art.

It has been found that the use of removable link-securing pins for this purpose is feasible if means are provided within the connected links for engaging those pins and reliably retaining them in assembled position by exerting upon them a force sufficient to produce a frictional resistance to movement. This frictional force can, however, be overcome if the pins are manually pushed or

2

pulled out from their assembled position. The disassembling force can readily be exerted upon the pin by means of any suitable pointed or thin tool. There is no real possibility that such a force could be exerted upon the link-securing pin in any accidental way so that the links are reliably connected to one another under normal circumstances. The jeweler, however, can readily detach and attach links at the point of sale.

To develop this frictional retaining force on the link-securing pins within the attached links, each of the links is provided with a resilient member, here shown as a strip of resilient metal, that resilient member being loosely retained within the link and having parts which normally extend into the link passages through which the link-securing pin is adapted to pass and being movable out from those passages, against the resiliency of the member itself, when the pin is inserted into those passages. It will, therefore engage the pin and press it against the passage walls with appreciable force, thus creating a frictional resistance to axial movement of the pin which reliably retains the pin within the link passages until such time as it may be manually pushed therefrom by using some appropriate simple tool.

To the accomplishment of the above, and to such other objects as may hereinafter appear, the present invention relates to the bracelet link structure as defined in the appended claims and as described in this specification, taken together with the accompanying drawings, in which:

FIG. 1 is a three-quarter perspective view, taken partially from above, of a portion of a link chain constructed according to the present invention, some of the links being shown as detachable and others as non-detachable, the links being covered by ornamental shells;

FIG. 2 is a bottom plan view of a series of interconnected links with the ornamental shells omitted;

FIG. 3 is a top plan view, on an enlarged scale, of several of the links of the present invention, with portions thereof partially broken away and cross sectioned and with one link-securing pin only partially inserted;

FIG. 4 is a cross sectional view taken along the line 4—4 of FIG. 3;

FIG. 5 is a cross sectional view taken along the line 5—5 of FIG. 3; and

FIG. 6 is a composite three-quarter perspective view showing the blank from which a link may be formed and also showing the link formed therefrom.

In the embodiment of the present invention here specifically disclosed the bracelet chain is formed at least in part from a plurality of articulately connected but readily disconnectable links, three adjacent such links, each of substantially identical construction, being generally designated A, B and C (see FIG. 1). Each link, on one side thereof and substantially intermediate its ends, has a projecting portion 2. On the other side thereof and at each end are projecting portions 4 between which a recess 6 is defined, each projecting portion 2 being receivable in the recess 6 in the next adjacent link. The intermediate projecting portion 2 of one link and the end projecting portions 4 of the next adjacent link have passages 8 and 10 respectively which are adapted to register when a projecting portion 2 is received within a recess 6, the passages 8 and 10 then collectively extending from one side surface of the bracelet to the other. The links are adapted to be connected to one another by a pin or the like 12 which is adapted to be inserted into the passages 8 and 10 from one of the side surfaces of the bracelet. A resilient means generally designated 14 is carried by each link and is designed to engage and resiliently press against the pin 12 in one or more of the passages 8 and 10, thereby to retain said pin 12 in position and prevent

it from accidentally escaping and thus breaking the continuity of the bracelet.

More specifically each link is formed from a sheet of metal or the like (see FIG. 6) having a bottom wall 16 from which central tongue 18 extends in one direction and end tongues 20 extend in the other direction. Tongue 18 is provided with groove 22 and tongues 20 are provided with grooves 24, so located that when the tongues 18 and 20 are reversely bent about the grooves 22 and 24 respectively so as to overlie and be spaced above the wall 16, the intermediate and end projections 2 and 4, the recess 6, and the lateral passages 8 and 10 are formed thereby. A tab 26 is bent up from the wall 16 along the inner edge of the recess 6, and tabs 28 are bent up from the wall 16 along the outer edge thereof to either side 15 of the intermediate projection 2.

The resilient means 14 is here disclosed in the form of a strip of resilient metal or the like which is adapted to rest on the wall 16 beneath the bent-over tongues 18 and 20. It has a central part 30 with a rounded surface 32 on one side thereof and with notches 34 on the other side thereof between which the tab 26 is received. Arms 36 extend out from central part 30 and terminate in ends having rounded surfaces 38 on the sides thereof opposite from the surfaces 32 and having notches 40 on the other side thereof within which the tabs 28 are received. The notches 34, 40 and the tabs 26, 28 retain the strip 14 against undue lateral or longitudinal movement, and the wall 16 and tongues 18 and 20 retain the strip against undue vertical movement.

In the normal unstressed condition of the strip 14 the surface 32 of central part 30 partially protrudes into the passage 8, and at the same time the surfaces 38 of the arms 36 partially protrude into the passages 10, those passages 8 and 10 being of a size snugly to receive the pins 12. When the pins 12 are pushed into the passages 8 or 10 they engage the surfaces 32 or 38 and cam the corresponding portions of the resilient means 14 out of their way against the resiliency thereof. Hence the surfaces 32 and 38 of the resilient means 14 will press the pins 12 forcibly against the side walls of the passages 8 and 10 in which they are received, thus developing a substantial frictional force on the pins 12 which will ensure that they will remain in position until a disassembling longitudinal force is directly and consciously exerted on them.

To assemble two links the intermediate projection 2 of one is inserted into the recess 6 of the other until the passages 8 and 10 register. A pin 12 is then inserted into the open end of one passage 10 and pushed therethrough and through the passage 8 and the other passage 10, thereby articulately connecting the two links and defining an axis about which the two links can pivot. To disassemble two links the pin 12 is pushed endwise out from the passages 8 and 10.

As the pin 12 moves through passage 10 its forward end meets surface 38 of resilient arm 36 and cams that surface laterally outwardly. This is resisted by the resiliency of the arm 36. At the same time the entire piece 14 is shifted so that the surface 30 is pressed more into passage 8 of its own link (the better to grasp and hold the pin 12 extending or to extend through that passage) and its other surface 38 is pressed more into the other passage 10. As the pin moves through passage 8 in the adjacent link its forward end meets surface 32 on the resilient means 14 in that other link and cams it out of the way. As the pin moves through the other passage 10 it engages the other surface 38 of the first mentioned resilient means 14 and cams it out of the way.

It will be seen that each pin 12 is retained in position 70 by means of resilient pressure exerted thereon by three different surfaces (38, 32 and 30) forming parts of two separate and distinct resilient pieces 14, one in each of the connected links. Each surface develops appreciable retaining force. Hence the overall result is one of great 75

security and ready attachment and detachment of links. The only tool needed for detachment is a pin or point sufficiently small to push the pin 12 out from the passages 8 and 10, at least to a degree sufficient so that its protruded end may be grasped and the pin 12 then pulled all the way out.

To shorten a bracelet a given link or links (e.g. the link B) is separated from its adjacent links A and C by pushing out the appropriate pins 12 and is removed from the linkage. The links A and C are reconnected by inserting the pin 12 after their respective projection 2 and recess 6 have been interfitted.

To lengthen a bracelet a given pair of adjacent links are separated and a new link or links are inserted therebetween.

Each of the links may be covered by an ornamental shell 42 (see FIG. 1), which may be rectangular in plan shape, thereby masking the projections 2, 4 and recesses 6 from view from above (compare FIGS. 1 and 2). 20 Portions of the end walls of the shells 42 are cut away, at 44, to expose the ends of the passages 10 and the ends of the pins 14 therein received, so that the attaching and detaching operations above described can be carried out. Not all of the links need be made detachable; sufficient 25 leeway in length adjustment is afforded if only five or six links are provided with the detachability feature. The non-detachable links 40 may be made identical with the detachable links A, B and C, except that the end walls of their shells 40 are not provided with the cutaways 44, 30 and the resilient means 14 may be omitted therefrom if desired, since the ornamental shell end walls may be relied upon to retain the pins 14 in position articulately connecting adjacent links.

The structure of the present invention is simple, inexpensive and exceptionally well adapted to mass production techniques. The differences between detachable and non-detachable links are greatly minimized. Detachability is achieved without any appreciable sacrifice in reliability or safety. The connecting pins 12 are held in place by a plurality of simultaneously and independently acting elements, thereby providing a built-in safety factor.

While but a single specific embodiment of the present invention has been here specifically disclosed, it will be apparent that it is but exemplary in nature, and that many variations may be made therein, all within the scope of the invention, as defined in the following claims.

I claim:

1. A bracelet comprising a pair of adjacent links, one having a recess and the other having a projecting portion 50 extending into said recess, said projecting portion having a first passage therethrough and said one link having a second passage open at an external surface of said one link and registering with said first passage, an element passing through said passages and accessible at said external surface of said one link, and a resilient member in said other of said links engaging said element as it extends through said first passage and frictionally retaining it in position, in which said projecting portion of said other link projects from an intermediate portion flanked 55 by body portions constituting opposite sides of said other link, said resilient member comprising an elongated element the ends of which extend into said body portions and an intermediate portion of which engages said element in said first passage.

2. The bracelet of claim 1, in which said other link and said resilient member have engaging parts limiting the permissible movement of said resilient member in the directions in which said passages extend.

3. The bracelet of claim 1, in which said body portions, at their sides opposite said projecting portion, define a recess therebetween into which the projecting portion of another adjacent link is receivable, said body portions having passages extending therethrough into which another link-securing element is adapted to be re-

ceived, the ends of said resilient element normally partially obstructing said last mentioned passages, thereby being adapted to engage said other link-securing element and frictionally retain it in position.

4. A link comprising a housing with an intermediate projecting portion on one side thereof and a pair of end projecting portions on the other side thereof defining a recess therebetween, a first passage through said intermediate projecting portion, second and third registering passages through said end projecting portions respectively, 10 and a resilient element in said housing having first, second and third parts normally partially obstructing said first, second and third passages respectively but movable out of said obstructing position against the resiliency of said element, thereby to engage link-securing elements inserted 15 into said passages and frictionally retain said link-securing elements in position.

5. The link of claim 4, in which said parts of said resilient element are provided with cam surfaces engageable with said link-securing elements as the latter are moved into said passages, thereby to permit said link-securing elements to be readily inserted into said passages.
